TIMEPIECE DIAL

Frederic Marti and Georges Braunschweig, both of 165
Rue Numa Droz, La Chaux de Fonds, Switzerland

Filed Sept. 13, 1957, Ser. No. 47,727

Term of patent 14 years

(Cl. D42—1)

Fig. 1

Fig. 2

Fig. 4

Fig. 3

FIG. 1 is a plan view of a timepiece dial, showing our new design;

FIG. 2 is a fragmentary cross-sectional view thereof taken on line 2—2 of FIG. 1;

FIG. 3 is a plan view of a modified embodiment of the timepiece dial; and

FIG. 4 is a plan view of another modified embodiment of the timepiece dial.

We claim:

The ornamental design for a timepiece dial, as shown and described.
